KEY CASE

Theodore R. Patrick, El Cajon, Calif.

Application November 15, 1956, Serial No. 43,780

Term of patent 14 years

(Cl. D87—3)

FIG. 1

FIG. 2

FIG. 3

Figure 1 is a perspective view of a key case, showing my new design, the key being shown merely for illustrative purposes.

Figure 2 is an end view of the key case with the straps thereof in open position; and

Figure 3 is a plan view of the key case with the straps in open position.

The side of the present key case which is opposite to the side shown in Figures 1 and 3 presents a similar appearance.

I claim:

The ornamental design for a key case, substantially as shown and described.
